Inventor
Emma Evans Clark

By Daniel F. Zemans.

Attorney

UNITED STATES PATENT OFFICE.

EMMA EVANS CLARK, OF HAMMOND, INDIANA.

MAIL CATCHER.

Application filed July 5, 1923. Serial No. 649,769.

To all whom it may concern:

Be it known that I, EMMA EVANS CLARK, a citizen of the United States, and a resident of Hammond, county of Lake, and State of Indiana, have invented an Improvement in Mail Catchers, of which the following is a specification.

The invention relates to mail or express receivers and deliverers.

10 An object of the invention is to provide a device having a safety arm to prevent the operator from stepping out of the car when operating it.

Another object of the invention is to provide 15 a device with an operating arm and an arm for holding a receptacle.

Another object of the invention is to provide 20 a device having a covered receptacle, said cover operated from within the car against spring resistance.

Another object of the invention is to provide 25 an arm having an anti-friction support formed integral therewith.

Figure 1 is a fragmental plan view of the 30 device showing it in place within a car.

Figure 2 is a vertical fragmental section of a car showing the device in place.

Figure 3 is a perspective view of the support.

30 Figure 4 is a cross-section taken through the support.

Figure 5 is a detailed view of the cover of the receptacle.

Figure 6 is an enlarged fragmental view 35 of the arm showing the anti-friction support and flexible control means.

A vertical shaft 10 is secured to the floor 40 of a car C by means of a flange 11. The upper end of said shaft is secured to the car by means of a bearing 12; a support 13 is rotatably mounted on said shaft and supported in place by a collar 14. An arm 15 extends outwardly from the support and is either integral therewith or fastened 45 thereto in some other suitable way.

The portion adjacent the outer end of said arm is cut out and bent downwardly as at 16 to form a support for the anti-friction roller 16'. From the outer end of this support a receptacle 17 is hung by flexible members 18. A cover 19 is pivotally secured to the side of said receptacle and has a torsion spring 20 to keep the cover closed normally.

55 The cover is of triangular form so that

when it is pulled open by flexible member 21 which is trained over the anti-friction roller 16 and through the arm to be accessible from within the car it will not interfere with the flexible members by which 60 said receptacle is hung.

The upper end of the support 13 is cut away as at 22 and a set-screw or stud 23 engages the shaft and cut away portion of the support to limit the angle of rotation 65 of said support.

In passing a railroad station or the like it is sometimes convenient to have the mail or packages extend outwardly away from the door of the car so that the mail clerk 70 can reach them from the window of the station or without getting close to the door of the car. It also happens sometimes that the operator of the device accidentally steps from the car. For this reason it is an object of the invention to have the short arm 75 24 by which the operator turns out the container close to the bar 25 which is provided to prevent his accidentally stepping from the car. When the receptacle is in this position the member 27 may be used to open the cover of the container. After the mail or packages have been put into it, it will close by the torsion of the spring on the cover. It is then turned back into the car. 80

I claim:

1. A receiver comprising a vertical shaft mounted in a car, rotatable arms supported on a collar secured to said shaft providing a self contained operating handle safety bar 90 and receptacle rod, a receptacle secured to one of the arms a cover for said receptacle operated by a flexible member connected thereto and passing through a central bore in one of said arms and means for limiting 95 the angle of rotation of the receiver.

2. In a receiver a vertical shaft fixedly mounted in a car rotatable arms mounted thereon one of which carries a container having a cover and means for opening said 100 cover from within the car.

3. In a receiver a vertical shaft fixedly mounted in the car arms rotatably mounted thereon an anti-friction support formed integral with one of said arms forming an 105 aperture to receive a flexible member provided for opening a container cover, from within the car, against spring resistance.

4. In a receiver a vertical shaft fixedly mounted in a car a support rotatably mount- 110

ed thereon, and arms of different lengths extending therefrom, a container hung from one of said arms, a triangular cover yieldingly mounted thereon and flexible means 5 passing through one of said arms for operating said cover from within the car.

In testimony whereof I affix my signature

in the presence of two witnesses at 7 So.
Dearborn St., Chicago, Illinois.

EMMA EVANS CLARK.
